CLAIM

I claim the ornamental design for a playhouse, as shown and described.

DESCRIPTION

FIG. 1 is an upper perspective view of the new design for a playhouse;

FIG. 2 is a lower perspective view of the design shown in FIG. 1;

FIG. 3 is a front elevation view of the design shown in FIG. 1;

FIG. 4 is a rear elevation view of the design shown in FIG. 1;

FIG. 5 is a right side elevation view of the design shown in FIG. 1;

FIG. 6 is a left side elevation view of the design shown in FIG. 1;

FIG. 7 is a top plan view of the design shown in FIG. 1; and,

FIG. 8 is a bottom plan view of the design shown in FIG. 1.

(Continued)

The broken lines shown in the drawings are included for the purpose of illustrating portions of the playhouse and form no part of the claimed design.

1 Claim, 8 Drawing Sheets
